UNITED STATES PATENT OFFICE.

GEORGE W. RIDDLE, OF HAMPTON, KENTUCKY.

SHOE-HOOK.

1,102,077.

Specification of Letters Patent. Patented June 30, 1914.

Application filed September 27, 1911. Serial No. 651,580.

To all whom it may concern:

Be it known that I, GEORGE W. RIDDLE, a citizen of the United States, residing at Hampton, in the county of Livingston and State of Kentucky, have invented certain new and useful Improvements in Shoe-Hooks; and I do hereby declare the following to be a full, clear, and exact description of the invention, such as will enable others skilled in the art to which it appertains to make and use the same.

This invention relates to shoe lace hooks, and has for its object to provide a device of this nature which will present a smooth appearance to the clothing or apparel located adjacent to the top of the shoe.

In the type of hooks now in use the same often become caught in the clothing, thereby being bent and broken, often damaging the clothing.

The present invention contemplates the elimination of all of these objectionable features and to provide a shoe hook which will be solid, substantial and inexpensive in its construction whereby the same will present a smooth surface to the clothing and will in no way be caught or engaged thereby.

With the above and other objects in view, this invention consists in the construction, combination, and arrangement of parts, all as hereinafter more fully described, claimed and illustrated in the accompanying drawings, wherein:

Figure 1 is a fragmentary elevation of the top of the shoe illustrating the hook forming the subject matter of the present invention applied thereto. Fig. 2 is the side elevation of a hook embodied in the present invention previous to the attachment thereof to a shoe. Fig. 3 is a central vertical section of a hook illustrating the same applied to a shoe.

The shoe lace hook forming the subject matter of the present invention is formed from a single sheet of metal in such a manner that no portion thereof may engage the clothing to damage either the hook or the apparel or clothing. The hook comprises a cylindrical body portion having a bead formed adjacent to a cover which extends entirely over the upper terminal of the body portion in such a manner that the openings existing in the shoe hooks heretofore are eliminated thereby excluding dust from the interior of the shoe. An outwardly extending loop is carried by the cover here-

tofore referred to and provides a means whereby the lace may be engaged by the hook.

Referring now more particularly to the drawings, 10 indicates the upper of a shoe provided with the usual tongue 11. A plurality of hooks A are secured to the shoe through the instrumentality of the riveting or swaging, which is now in use. The construction of the hooks however, differs entirely from those now in use. These hooks comprise the tubular or cylindrical body portion 12 which is closed at its upper terminal by the metal cover 13, said metal cover being formed from the body portion 12. A bead 14 extends around the exterior surface of the upper terminal of the body portion and provides a means whereby leather of the upper 10 may be retained in positive engagement with the hook, as will hereinafter be more fully described. A loop 15 is formed from the body portion 12 and extends above the cover 13, the arms 15' abutting on each other adjacent to the cover 13 and gradually diverging as they extend from the body portion 12, forming an enlarged loop 16, said loop being bent inwardly to form the lace retaining opening 17.

From this construction it will readily be understood that the hook forming the subject matter of the present invention will present absolutely no sharp edges or surfaces to catch in the apparel of the wearer to damage the latter or the hook.

In attaching the hooks forming the subject matter of the said invention to the upper 10 a series of apertures or holes are punched in the upper in the usual manner, 95 after which the tubular body portion 12 of one of the hooks is inserted in one of the openings thus formed in such a manner that the bead 14 rests against the outer surface of the upper. The body portion is then offset in an outward direction forming the retaining flange 18 which in combination with the bead 14 rigidly and firmly secures the hook to the upper.

Having thus fully described my invention, 105 what I claim as new, and desire to secure by U. S. Letters Patent, is:

A lacing stud comprising a cylindrical body portion having a closed end, an outwardly extending annular flange integral 110 with the side wall and flush with the closed end of said body portion, a closed loop

formed integral with the body portion, at a point spaced from the edge of the flange upon one side thereof, the closed end of said loop extending outwardly at right angles 5 to the closed end of the said body portion for a portion of its length, said loop turned inwardly and expanded at the outer terminal of the closed end thereof to form a recess adapted to receive a shoe lace, the lower 10 terminal of said turned-in portion affording a substantially flat surface centrally of its ends and spaced from the closed end of the

body portion to form a passage having enlarged terminals, the lower terminal of the inner side of the turned-in portion being 15 slightly spaced from the closed end of said loop at a point centrally of its ends to form a reduced opening for said recess.

In testimony whereof, I affix my signature in presence of two witnesses.

GEORGE W. RIDDLE.
